US00D877231S

(12) **United States Design Patent** (10) **Patent No.:** **US D877,231 S**
(45) **Date of Patent:** **** Mar. 3, 2020**

(54) **INTERACTIVE CAMERA DEVICE**

(71) Applicant: **Amazon Technologies, Inc.**, Seattle, WA (US)

(72) Inventors: **Matthew Michael Seflic**, San Jose, CA (US); **Marc Rene Walliser**, San Francisco, CA (US); **Christopher Green**, San Francisco, CA (US)

(73) Assignee: **Amazon Technologies, Inc.**, Seattle, WA (US)

(**) Term: **15 Years**

(21) Appl. No.: **29/629,097**

(22) Filed: **Dec. 11, 2017**

Related U.S. Application Data

(62) Division of application No. 29/569,667, filed on Jun. 29, 2016, now Pat. No. Des. 808,454.

(57) **CLAIM**

The ornamental design for an interactive camera device, as shown and described.

DESCRIPTION

FIG. 1 is a front perspective view of an interactive camera device;

FIG. 2 is a rear perspective view of the interactive camera device as shown in FIG. 1;

FIG. 3 is a front view of the interactive camera device as shown in FIG. 1;

FIG. 4 is a back view of the interactive camera device as shown in FIG. 1;

FIG. 5 is a left-side view of the interactive camera device as shown in FIG. 1;

FIG. 6 is a right-side view of the interactive camera device as shown in FIG. 1;

FIG. 7 is a top view of the interactive camera device as shown in FIG. 1; and,

FIG. 8 is a bottom view of the interactive camera device as shown in FIG. 1.

The broken lines depict portions of the interactive camera device which form no part of the claimed design.

1 Claim, 7 Drawing Sheets
